MICROMETER

Samuel George Zuckerman, New York, N. Y.

Application December 16, 1949, Serial No. 133,226

9 Claims. (Cl. 33—166)

1

This invention relates to micrometer calipers, particularly to direct reading micrometers.

The most widely used micrometer is the conventional screw type device in which the operative turning of the micrometer screw causes the contact face at the end of the spindle to move towards or away from the anvil, the rotary movement of the screw bearing a predetermined relation to the longitudinal movement of the spindle. Thus, in English measure micrometers, the customary pitch is .025", so that for each complete revolution of the screw there is a longitudinal spindle movement of .025", the scale on the barrel containing graduations of .025", and the beveled edge of the thimble rotatable about the barrel being graduated into 25 parts, so that each graduation represents .001". To read a measurement, it is accordingly necessary to perform three steps, to wit, (1) take note of the highest figure visible on the barrel, (2) add .025" for each graduation visible between that figure and the thimble edge, and (3) add to this sum the number of the graduation on the thimble which coincides with or is nearest to the longitudinal reference line on the barrel.

Thus, with the conventional micrometer caliper, a number of operations are required which are not only time-consuming, but which render the readings subject to possible error. Yet, despite these shortcomings, this type of micrometer is preferred to any other known type, because of the inherent accuracy of the screw mechanism. In other words, it is only the rotary movement of the spindle which effects its operative longitudinal movement, without any intermediate moving elements to produce a cumulative sequence of lost motions, such as by back-lash, inaccurate interfittings and progressive wear.

The various attempts to produce micrometers with direct-reading visual indicating means have met with no appreciable commercial acceptance.

Certain of these attempts have resulted in devices containing dials or pointers rotatably actuated by gearing disposed intermediate the rotatable spindle and the dial or pointer. While these devices have a field of use, they are not comparable in accuracy to the micrometer screw type, because of the intermediate gearing, and hence are not suitable for close work. Other direct-reading micrometers have had the required degree of accuracy, but only for a limited range, enabling direct readings to be taken only for one or two turns of the spindle, beyond which readings must be taken on another scale.

It is primarily within my contemplation to pro-

vide a micrometer particularly, although not exclusively, of the caliper category, which has all the advantages with respect to accuracy of the conventional screw micrometer, and yet which will give direct readings without the shortcomings of other direct-reading devices. More specifically, it is my objective to present a micrometer which will give direct readings, quickly and without the need to make any arithmetical computations, which will have as wide a range as the conventional screw micrometer, which employs no intermediate gearing or other mechanism for controlling the longitudinal movement of the spindle, and which will be as convenient to handle as the conventional screw micrometer.

More specifically, it is an object of my invention to employ a spindle containing threads thereon for controlling the longitudinal movement of the spindle, and a longitudinal scale on a barrel, substantially of the type used on conventional screw micrometers, but instead of the circumferential scale on the beveled edge of the thimble (as in conventional structures), to employ in combination with the spindle a helical scale the length of which is sufficiently great to enable a hundred graduations, each representing .001" in convenient and easily spaced arrangement. And it is my object to provide, in combination with such a helical scale, special means, which in themselves need not be fabricated with close tolerances, to enable direct readings to be taken on the scale.

And in the last-mentioned aspect of my invention, it is a specific object to provide a rotary indicator, coactive with the said helical scale, which will require negligible power for its operation, and which may have geared interconnecting means and play between associated gear teeth, without affecting its accuracy.

Still another object of my invention is to provide a stationary vernier scale which will at all times remain in close juxtaposition to its coactive rotary scale actuated by the rotation of the spindle.

It is another object of my invention to provide the aforesaid helical scale with a helical groove serving the double function of separating the figures on adjacent convolutions of the scale, for clarity, and serving as a worm actuating means for the rotary indicator of my invention.

Still another object is to provide a guard serving the double function of protecting the interior of the device against the infiltration of dust, and serving as a finger support to prevent manual interference with the rotary operation of the device.

2

It is within my contemplation to provide a device having the aforesaid features and advantages, and which is nevertheless simple to operate and easy to fabricate. And in the last-mentioned aspect of my invention it is an object to enable this device to be manufactured by employing the major portion of the fabricating machinery used in producing conventional screw micrometers.

Other objects, features and advantages will appear from the drawings and the description hereinafter given.

Referring to the drawings,

Figure 1 is a side view of a micrometer constituting a preferred form of my invention, the spindle being shown in contact with the anvil.

Figure 2 is a top view of Figure 1, but with the end of the spindle spaced from the anvil.

Figure 3 is an enlarged fragmentary view of a portion of Figure 1, with the plate covering indicator disc removed, fragments being broken away for clarity, the parts being shown in the position of Figure 2.

Figure 4 is a fragmentary enlarged portion of Figure 1.

Figure 5 is an enlarged section of Figure 1 taken along line 5—5.

Figure 6 is a fragmentary disassembled top view, partially in section, of Figure 1, the thimble and spindle being shown entirely withdrawn.

Figure 7 is a fragmentary side view, substantially like Figure 3, but showing a modified form of my invention.

Figure 8 is a top view of Figure 7.

Figure 9 is a section of Figure 7 taken along line 9—9.

Figure 10 is a view like Figure 7, but showing another setting of the device, and

Figure 11 is a perspective view of the cover plate, window and reference line, of the type used in the modification of Figure 7.

In the form of my invention illustrated in Figures 1 to 6, the micrometer caliper comprises a frame 15 containing an anvil 16 adapted to receive thereagainst the end 17 of the spindle 18, said spindle being provided, as will more clearly hereinafter appear with a rear threaded portion substantially like that on conventional screw micrometers, whereby upon an operative turning of the spindle 18 and associated parts, it will move longitudinally to and from the anvil 16. The said spindle extends through the two opposite walls 19 and 20, the rear terminal portion 21 of the spindle being recessed at 22 to receive therein the screw member 23, the head of which rests upon the shoulder 24 in the central aperture 25 of the thimble member 26. The arrangement is hence such that the spindle 18 is affixed to said thimble member 26, and rotates together therewith, in known manner. The threaded portion 27 of the spindle is adapted for operative engagement with the inner threaded portion 28 of the nut 29 which contains a threaded shank 30 extending into and in threaded engagement with the rear of the hollow barrel 31. When the parts hereinabove described are in assembled relation, it is evident that a rotary manipulation of sleeve 26 will cause a corresponding rotation of spindle 18; and since portion 27 thereof is in threaded engagement with portion 28 of stationary nut 29, the rotation of thimble 26 will consequently cause a longitudinal movement of the spindle 18 which extends through the spindle bore 32 of the barrel 31. The parts thus far described are substantially similar to those of the conventional micrometer, the threads 27 having, in the par-

ticular form of my invention illustrated, a pitch of .025".

Disposed between the said walls 19 and 20 of the frame is the drum 33, this containing an axial bore 34 through which extends the said spindle 18. Extending substantially radially inwardly from the outer surface of drum 33 is the pin or key 35, said pin being proportioned to extend into the keyway or groove 36 extending longitudinally preferably from the end 17 of the spindle to the region of the thread portion 27. The pin 35 is adapted for slidable movement within the groove 36, longitudinally therewith, as will more clearly hereinafter appear. Thus, upon a rotation of spindle 18, the drum 33 will also rotate therewith, through the action of said pin 35. However, the pin will not interfere with the longitudinal operative movement of the spindle 18, because of the slidable engagement of said pin with groove 36.

The said drum 33 contains thereon the helical scale 37, the convolutions thereof being separated by the helical groove 38. The arrangement is such that the helical groove 38 makes a worm out of drum 33, in coactive engagement with the teeth 39 of gear 40. Said gear is rotatably mounted on the shoulder screw 41, the shank 42 of which is in threaded engagement with the wall 43 of frame 15, the head 44 of the screw permitting a free rotation of the gear 40. Mounted over the annular flange 45 of the gear is the indicating disc 46, the particular form showing this disc having an inner annular wall 47 press-fitted over annular wall 45. It is preferred that the outer diameter of the disc 46 be sufficiently great that the disc overlap the drum 33, as shown in Figure 3, and yet out of contact therewith, for reasons which will hereinafter appear. The outer face of the disc is provided, in the particular form illustrated, with five dots 48, 49, 50, 51 and 52, these being adjacent the outer periphery of the disc 46.

Disposed over the disc 46 is the plate 53, secured to frame 15, said plate having an arcuate aperture or window 54 adjacent the upper edge 55 of the said plate 53. Said upper edge constitutes the reference line along which readings are taken, as will be hereinafter explained.

It will be seen that the drum 33 has, in the particular form illustrated, five helical convolutions 56, 57, 58, 59 and 60 carrying the said helical scale 37 comprising four complete scale convolutions. The aperture 54 is of a length so as to extend at least across all of said convolutions. And the said indicating dots 48 to 52 are equally spaced on the disc 46, the spacing being such that when any two are on a line parallel to the axis of the spindle, they will be opposite the two outermost convolutions 56 and 60. For example, by referring to Figure 3, it will be seen that the space between the indicating dots 48 and 49, which are on a line parallel to the axis of the spindle, is substantially equal to the median distance between the extreme opposite convolutions 56 and 60, the dots being opposite the said respective convolutions. It is to enable such a positioning to be effectuated that the disc 46 has been made in overlapping relation to the drum 33, as aforesaid. It will thus be observed (Figure 1) that when two indicating dots are opposite the said two outermost convolutions 56 and 60, they will be visible through the aperture 54.

The calibrations 61 on the barrel 31 give tenths of an inch, the spacing between each calibration

representing four turns of the spindle 18. The calibrations on the helical scale 31 represent hundredths of an inch, there being one hundred such calibration lines on the helical length of four convolutions, a single convolution representing .025". The said calibrations 61 on the barrel are thus multiples of the calibrations on scale 37. The wall 19 of the frame contains thereon the stationary vernier calibrations 62; and the adjacent terminal edge portion 63 contains thereon coacting calibrations, the relationship of the calibrations 62 and those on portion 63 being similar to conventional vernier calibrations and need not therefore be described.

In the operation of this instrument, a measurement is taken of a selected object operatively disposed between the anvil 16 and the spindle 18 in the usual way. During the manual rotation of the thimble 26 and the concomitant rotation of the spindle 18, the indicating disc 46 is operatively rotated, in the manner indicated. This causes the indicating means, that is, the said dots on the disc to move through an arc which is in intersecting relation to the directions of all the convolutions on the scale, the diameter of the disc being no less than, and preferably greater (as illustrated) than the length of said helical scale 37 measured along its longitudinal axis. When the anvil 16 and spindle 18 are in operative contact with the object being measured, there will be one (or at most two) of the said dots adjacent and in substantial longitudinal alignment with one (or at most two) of said convolutions, enabling a direct reading to be taken in the manner to be hereinafter set forth.

By referring to Figures 1 and 4, the setting for zero reading is illustrated. The reference edge 64 of the beveled portion 65 of the thimble 26 is directly on the zero line of the scale on barrel 31; the reference edge 55 of plate 53 is coincident with the zero line on convolution 56 of the helical scale; and only the zero calibration on stationary vernier scale 62 is in longitudinal alignment with a calibration line on vernier scale 63. It will also be noted that indicating dots 48 and 49 are both exposed to view, and opposite the extreme convolutions (56 and 60), the readings on said convolutions, taken with reference to edge 55, both indicating no readings other than zero. The reading on barrel 31, as aforesaid, indicates zero; and the reading on the vernier indicates zero; accordingly, the total reading is .0000".

When the setting is as shown in Figures 2 and 3, the reference edge 64 of the thimble is in line with the calibration marking .1. Indicating dot 52 is opposite convolution 56; and the reference edge 55, as well as the vernier readings, indicate zero as the reading on drum 33. Therefore, the exact reading for the setting of Figure 4 is .1000".

Figures 7 and 10, which illustrate another modification to be hereinafter described, show other readings which will help the understanding of this device. Referring to Figure 7, the reference line 55a is analogous to reference edge 55 of the first form shown. The reference edge 64a of the thimble 26a is positioned beyond the marking for .1". The reference dot 66 is positioned opposite the convolution 68, which merely means that the reading must be taken on that convolution. The reference line 55a is disposed in line with reading .070; and the vernier reading indicates zero. Therefore the reading for the setting of Figure 7 is .1700".

Referring now to Figure 10, it will be seen that the reference edge 64a of the thimble 26a is disposed beyond the numeral .4 on the barrel. The indicating dot 69 is disposed opposite convolution 67, thereby indicating that the reading must be taken on that convolution. The reference line 55a is positioned beyond calibration line .024; and the vernier indicates a .0002 reading, since a calibration marking on the rotary scale 70 of the vernier is in longitudinal alignment with the numeral "2" on the stationary portion 71 of the vernier. It is thus apparent that the direct reading, without any arithmetical computations, is .4242".

From the above description it will be seen that all that need be done is to rotate the thimble in conventional manner, until the spindle and anvil engage the object to be measured. The rotation of the spindle does two things; it causes the reference edge 64 (or 64a) of the thimble to move longitudinally along the barrel, and also causes the disc 46 to rotate, since the rotation of drum 33 produces a rotating of coacting gear 40 which carries the disc 46. The accuracy characteristic of the screw micrometer is inherent in this invention, since the longitudinal movement of reference edge 64 and the rotary movement of drum 36 are controlled only by the accurate threads 27 which are capable of exceedingly close tolerances. There is no need for any undue accuracy with respect to the gear 40, since this gear merely carries the indicator disc 46 which itself carries no scale nor points to a specific marking on any scale. This disc merely indicates where a reading is to be taken, and it matters not if there is a little play between the gear teeth, since that need only affect the position of the indicating dot with respect to a particular convolution. As long as the dot is opposite portion of the convolution, it serves its intended purpose. It may be exactly on the medial line of the convolution, or somewhat to the right or left; but it will still indicate which convolution will give the reading. The only close tolerances that are required are in the screw thread 27, and in the pin and slot combination 35 and 36. Since the same tolerances that are applied in conventional screw micrometers can apply in the instant case, this device will be as accurate as such conventional structures, in so far as the screw thread is concerned. As to the pin and groove tolerances, it is known that this type of construction permits of the closest possible accuracy. Experience has proven that with this particular construction, conventional fabricating methods will permit a tolerance of approximately .0003" between the pin and walls of the groove, and this may amount to a possible error of one hundred thousandths of an inch, which is negligible.

Since the gear 40 and the disc 46 perform no work other than to bring the indicating dots to their proper positions, these elements may be made of light-weight material; and hence practically no load whatsoever is imposed upon the instrument because of these elements.

It will further be observed that the movable portion of the vernier is always adjacent the stationary portion, since the rotating drum does not move in an axial direction. This arrangement assures easy and close reading of the vernier.

By referring to Figure 5 it will be seen that the rear of the instrument contains a guard member 72 attached to the frame 15. This serves a two-fold purpose. In the first place, it seals the space 73 leading into the interior of the mechanism;

and in the second place, it serves as a finger rest so that, in operatively holding the micrometer, the fingers will rest against the guard and not interfere with the barrel 33.

The form of my invention illustrated in Figures 7 to 11 embodies substantially the construction shown in Figures 1 to 6, except that a transparent window construction is added. More specifically, instead of the plate 53 of Figure 1, a substantially U-shaped plate 74 is used, the short leg 75 extending over the top and rear of the device. Suitably secured to the inside of the plate is the transparent sheet 76. The aperture 77 in the plate exposes a portion of the transparent sheet, to provide a window 78 for the drum 33a. Said window contains thereon the reference line 55a like the hairline on a slide rule.

As aforesaid, this line 55a is analogous to reference edge 55 of the form first above described. However, the portion 79 of the window below reference line 55a exposes the lower portion of the drum 33a to view. This makes it easier to effect the reading. Furthermore, the entire drum is completely sealed by the plate 74 and window 78, providing a dust-proof, yet readily visible structure. The aperture 80, formed in the wall of plate 74, is analogous to aperture 54 of the first form described.

It will be observed that since both forms of this invention embody the conventional elements of a spindle with .025" pitch threads thereon, a thimble with beveled edge, a barrel, an internally threaded nut in engagement with the threaded portion of the spindle, the fabricating equipment now used for making conventional micrometer screws may still be employed in the manufacture of these basic components. It is estimated that the additional components such as the frame, drum, gear, indicating disc and associated parts can be fabricated without great difficulty and with conventional fabricating equipment. Accordingly, the conversion of present micrometer fabricating plants to produce the present device can be effectuated without excessive cost.

In the above description, the invention has been disclosed merely by way of example and in preferred manner; but obviously many variations and modifications may be made therein. It is to be understood, therefore, that the invention is not limited to any specific form or manner of practicing same, except in so far as such limitations are specified in the appended claims.

I claim:

1. In a micrometer of the class having a frame provided with an anvil, a calibrated barrel, a 55 rotatable thimble and a spindle rotatable with the thimble and movable toward and away from the anvil, the combination of a helical scale member connected to and rotatably movable with said spindle, said scale member having a plurality of convolutions bearing scale calibrations thereon, rotatably mounted indicating means coaxially rotatable with the spindle, a portion of the arc of rotation of said means being along a path intersecting the directions of all the convolutions 65 of the helical scale, and, a reference line parallel to the axis of the helical scale and extending across all the convolutions thereof.

2. In a micrometer of the class having a frame provided with an anvil, a calibrated barrel, a 70 rotatable thimble and a spindle rotatable with the thimble and movable toward and away from the anvil, the combination of a helical scale member connected to and rotatably movable with said spindle, said scale member having a plurality of

convolutions bearing scale calibrations thereon, a reference line parallel to the axis of the helical scale and extending across all the convolutions thereof, and rotatably mounted indicating means coaxially rotatable with the spindle, the portion of the arc of rotation of said means nearest said reference line being along a path intersecting the directions of all the convolutions of the helical scale.

3. In a screw micrometer, an anvil, a rotatable spindle movable toward and away from the anvil, a helical scale member connected to and rotatably movable with said spindle, a rotatably mounted indicating disc coaxially rotatable with the spindle, a peripheral portion of the disc overlapping a portion of the said scale, a plurality of spaced indicating means on the peripheral portion of the disc, and a plate overlying the disc, the plate having an apertured portion adjacent the helical scale, the diameter of said disc being no less than the length of said helical scale member measured along its longitudinal axis, whereby upon an operative rotation of the disc the indicating means will move along an arcuate path intersecting the directions of all the convolutions of the helical scale, the said apertured portion overlying a peripheral portion of the disc to expose the said indicating means when operatively adjacent the helical scale.

4. In a screw micrometer, an anvil, a rotatable spindle movable toward and away from the anvil, a helical scale member connected to and rotatably movable with said spindle, a rotatably mounted indicating disc coaxially rotatable with the spindle, a peripheral portion of the disc overlapping a portion of the said scale, and a plurality of spaced indicating means on the peripheral portion of the disc, said means comprising markings so spaced that the distance between adjacent markings measured in a direction parallel to the axis of the helical scale member is substantially equal to the median distance between the extreme opposite convolutions bearing said scale calibrations, and a plate overlying the disc, the plate having an apertured portion adjacent the helical scale, the said apertured portion overlying a peripheral portion of the disc and being of a length at least equal to the distance between the two said extreme opposite convolutions, whereby two adjacent markings may be simultaneously exposed by said apertured portion.

5. In a screw micrometer, an anvil, a rotatable spindle movable toward and away from the anvil, a helical scale member connected to and rotatably movable with said spindle, a rotatably mounted indicating disc coaxially rotatable with the spindle, a peripheral portion of the disc overlapping a portion of the said scale, a plurality of spaced indicating means on the peripheral portion of the disc, a plate overlying the disc, the plate having an apertured portion adjacent the helical scale, the diameter of said disc being no less than the length of said helical scale member measured along its longitudinal axis, whereby upon an operative rotation of the disc the indicating means will move along an arcuate path intersecting the directions of all the convolutions of the helical scale, the said apertured portion overlying a peripheral portion of the disc to expose the said indicating means when operatively adjacent the helical scale, and a reference line parallel to the axis of the helical scale and extending across all the convolutions thereof.

6. In a micrometer, the combination according to claim 5, said reference line comprising the edge 75 of the said plate nearest the helical scale.

7. In a micrometer, the combination according to claim 5, further provided with a transparent window disposed over the scale, and a line on said window constituting said reference line.

8. In a micrometer, the combination according to claim 5, said plate being of substantially U-shaped cross-section with one long and one relatively short leg, the said long leg overlying the disc, the said short leg being disposed behind said helical scale, the intermediate portion of the plate between said legs extending over the top of the scale, and a window in the plate disposed over a portion of the scale, said window having a line thereon constituting said reference line.

9. In a screw micrometer, an anvil, a rotatable spindle movable toward and away from the anvil, a drum mounted over the spindle, the spindle being in slidable engagement with the drum for longitudinal movement, connecting means between the drum and spindle, whereby they will rotate together, said drum having on the outer surface thereof a helical scale, a rotatably mounted indicating disc coaxially rotatable with the spindle, a peripheral portion of the disc overlapping a portion of the said scale, a plurality of spaced indicating means on the peripheral portion of the disc, a plate overlying the disc, the

plate having an apertured portion adjacent the helical scale, the diameter of said disc being no less than the length of said helical scale member measured along its longitudinal axis, whereby upon an operative rotation of the disc the indicating means will move along an arcuate path intersecting the directions of all the convolutions of the helical scale, the said apertured portion overlying a peripheral portion of the disc to expose the said indicating means when operatively adjacent the helical scale, and a reference line parallel to the axis of the helical scale and extending across all the convolutions thereof.
